UNITED STATES PATENT OFFICE.

CHARLES SCHATZLE AND EDWIN SMITH, OF PALMERTON, PENNSYLVANIA.

SIGNALING DEVICE.

1,194,668.

Specification of Letters Patent. Patented Aug. 15, 1916.

Application filed September 13, 1915. Serial No. 50,449.

To all whom it may concern:

Be it known that we, CHARLES SCHATZLE and EDWIN SMITH, citizens of the United States, residing at Palmerton, in the county 5 of Carbon, State of Pennsylvania, have invented certain new and useful Improvements in Signaling Devices; and we do hereby declare the following to be a full, clear, and exact description of the invention, such as will enable others skilled in the art to which it appertains to make and use the same.

This invention relates to certain novel and useful improvements in an electric signaling device, intended particularly for location at the intersection of streets, tracks or roads, or at sharp curves and corners for the purpose of preventing collisions between vehicles approaching each other along intersecting ways.

In carrying out our invention it is our purpose to provide a signaling device which embodies among other features a plurality of signals which are located at the intersection of two roads or ways, or at a curve or bend in a road or way, these signals being so arranged and operated that a vehicle, such as an automobile or the like, traveling along one section of road in the direction of the signals, will at a predetermined point operate one of the signals which may be readily observed for a considerable distance by a second vehicle approaching the signal from another or intersecting section of road or way, so that an occupant of such last mentioned vehicle will be notified of the danger of an approaching vehicle and may consequently exercise the necessary caution to avoid collision or accident.

Still a further object of our invention is to provide an electric signaling device, wherein the signal may be set at danger by the closing of the circuit when the vehicle passes over one section of the roadway, and returned to normal or clear position by the breaking of the circuit when the vehicle passes over another section of the roadway.

It is also our purpose to provide a signaling device which will embody the desired features of simplicity, efficiency and reliability, and which embodying as it does but relatively few parts, may be manufactured and installed at a comparatively low cost.

With the above recited objects and others of a similar nature in view, our invention consists in the construction, combination and

arrangement of parts set forth in and falling within the scope of the appended claims.

In the accompanying drawing: Figure 1 is a top plan view of a signaling device embodying our invention. Fig. 2 is a side elevation showing the circuit opening and closing devices of one of the signaling members in exposed position. Fig. 3 is an end view. Fig. 4 is a sectional view taken on the line 4-4 of Fig. 1.

Before entering into a detailed description of our invention, we will briefly state that in the preferred form shown herein, it embodies among other features a suitable support, such as a post or the like, located at a corner, or where two sections of road intersect, this support carrying two signals, preferably electric lamps, equipped with red bulbs or lights. A suitable shield or reflecting device is provided, which is interposed between the two lamps in such manner that one of the lamps when lighted may be observed by the occupants of the vehicle traveling toward the signal along one section of the road, but will be obscured from the vision of the occupants of a vehicle traveling along the other or intersecting section of the road. In other words, a vehicle traveling along one section of the road will at a certain point, operate mechanism to display the danger signal for the opposite or intersecting section of road, and will subsequently further operate such mechanism to restore the signal to its normal clear position. In the present instance each section of the road is provided with one depressible member for closing the electric circuit and two depressible members for breaking the electric circuit of one of the signals, for the purpose hereinafter apparent.

Referring now to the accompanying drawings in detail, the letter A indicates one section of a roadway, and the letter B indicates another section of a roadway, the two sections intersecting or meeting at the corner C. At the corner C we arrange a post 1, upon which is mounted a suitable platform P, this platform including the intermediate section 3 and the end sections 4 and 5. The platform end section 4 has mounted thereon, in the present instance, a suitable signal lamp L, while the platform end section 5 is likewise equipped with a signal lamp L', and it will be observed that the platform is so mounted on the post that the signal lamp L is in alignment with and may be observed

by a person traveling toward the signal along the road A, while the signal L' may be likewise observed by a person traveling toward the signal along the road B. An 5 approximately V-shaped shield or reflector S is mounted on the platform, as shown in the drawings, so that the curved section 6 of the shield acts as a reflector for the lamp L, while the curved section 7 of the shield acts 10 as a reflector for the lamp L', and at the same time the apex section of the shield projects between the two lamps. As heretofore stated, these lamps are preferably in the nature of electric lamps, and are lighted 15 from suitable batteries (not shown).

Alongside the road section A is arranged the circuit closing and circuit breaking mechanism for the lamp L', or that lamp which acts as a signal for the road section B, 20 while alongside the road section B is arranged the circuit closing and breaking mechanism for the lamp L, or that lamp which acts as a signal for the road section A. As the circuit opening and breaking mechanism for one lamp is identical in construction with that of the other lamp, a description 25 of one will suffice for both.

Suitably located, for instance alongside the road A, and protected in any preferable 30 manner, is a push button device D from which lead the usual conductors 8 and 9, to the lamp L', or that lamp acting as a signal for the road section B. This push button is operated by the following circuit closing 35 and opening mechanism: Extending transversely of the road section are three grooves or slots, adapted to receive the depressible bars 13, 14 and 15, each of these bars being provided with depending coil springs 16 fitting 40 into sockets 17 in the bottom of its respective groove. The bar 13 when depressed is intended to break or open the circuit to the lamp L', the intermediate bar 14, when depressed is intended to close the circuit to the lamp L' to light the latter, while the bar 45 15, or that nearest the signal post, when depressed is intended to break the circuit to extinguish the lamp L'. Pivoted as at 18 beneath the bar 13 is an arm 19, the upper 50 end of which is adapted to be contacted with by the depressible bar 13, and pivoted to this arm 19 intermediate its ends as at 20, is a link rod 21, the opposite end of which is provided with a contraction spring 22 connected as at 23 to the intermediate portion 55 of the arm 24, which is adapted to be contacted with by the depressible closing bar 14. This arm 24 is pivoted at its lower end as at 25, and has connected thereto as at 60 26, one end of the link bar 27, the opposite end of said link bar having formed therewith the extension spring 28 which is fastened as at 29 to the arm 30, pivoted as at 31. The lower end of this arm 30 is bent 65 laterally and horizontally as at 32 and termi-

nates at the push button D, while the upper end 33 of the arm lies directly beneath and is adapted to be contacted with by the depressible circuit opening bar 15.

From the above description, taken in connection with the accompanying drawings, the construction and operation of the device so far described, will be readily apparent. Assuming an automobile for instance, to be traveling along the road A in the direction of the signaling post at the corner of the roads, the automobile will first pass over the depressible bar 13 and depress the latter. However, as this is a circuit opening bar the lamp L' will not be lighted, for 70 this bar is for a purpose hereinafter described. As the automobile continues its journey, however, and strikes the depressible closing bar 14, it will press the latter into contact with the end of the arm 24 and 75 move the latter on its pivot, thereby pulling on the link rod 27 and consequently swinging the arm 30 on its pivot and causing the end 32 of the arm to press the push button device D, and thereby close the circuit from 80 the batteries (not shown) to the lamp and cause the lamp to be lighted. As the automobile in its travel passes over the circuit opening bar 15, which is substantially at the 85 corner or intersection of the roads, it will 90 depress this bar against the end 33 of the arm 30, and thus swing this arm on its pivot to release the push button to break the circuit to the lamp L'. When the circuit is 95 thus broken by the depression of the bar 15, the vehicle is substantially at the corner or intersection of the roads, so that it might 100 be readily seen by the occupants of a vehicle approaching on the road B. The distant circuit opening depressible bar 13 is employed, 105 because when a vehicle is traveling on the road A away from the signal, it will in its passage over the circuit closing bar 14, depress the latter and light the lamp L', although the vehicle is traveling away from 110 the signal and consequently this distant circuit opening bar 15 is employed for extinguishing the lamp when so lighted.

Of course, it is to be understood that the 115 electric circuit for the lamps may be arranged in an ordinary and well known manner and that suitable batteries may be used to supply current to the lamps, but as the particular wiring of the device forms no essential part of the invention, it need not 120 be described in detail. It is further to be understood that the circuit opening and closing mechanism, described for operating the lamp L' by a vehicle traveling along the road A, is duplicated alongside the road B, 125 for the purpose of operating the lamp L.

It will thus be observed that we have provided an exceedingly simple, yet positive and efficient means by means of which the 130 occupants of a vehicle traveling along one

section of a road which intersects or meets another road section at an angle, may be warned of the approach of a vehicle on such other road section.

5 While we have herein shown and described one particular embodiment of our invention, we wish it to be understood that we do not confine ourselves to all the precise details of construction herein set forth by 10 way of illustration, as modification and variation may be made without departing from the spirit of the invention or exceeding the scope of the appended claims.

What we claim is:

15 1. The combination with a suitable support, of an electric signal mounted thereon and means for making and breaking an electric circuit for the signal, said means including an intermediate pivoted arm, a pair 20 of oppositely extending links connected with said arm, a second pivoted arm connected with one of said links, a third pivoted arm connected to the other of said links, a push button connected with the signal and 25 operable by the third arm, and a depressible member for operating each arm.

2. The combination with a suitable support adapted to be located at the intersection of two roadways, of a pair of electric 30 lamps each arranged to act as a signal for

a respective section of roadway, a shield interposed between the two lamps, and means located at each roadway and operable by a passing vehicle for opening, then closing and then opening the electric circuit of the 35 signal lamp at the other roadway.

3. The combination with a suitable support adapted to be located at the meeting point of two roadways, of a pair of electrically operated signaling devices mounted 40 on the support, one of said devices for each roadway, and means located at one roadway for controlling the signaling device of the other roadway, said means including an electric switch for controlling an electric 45 circuit to said signaling device, and means for operating the switch, said means including a series of depressible bars, a member operated by the depression of each bar, connections between all of said members, 50 and means carried by one of said members for operating directly upon the switch to open and close the latter.

In testimony whereof, we affix our signatures in the presence of two witnesses.

CHARLES SCHATZLE.
EDWIN SMITH.
